UNITED STATES PATENT OFFICE.

FLOYD A. RICE, OF SPRINGFIELD, OHIO.

PLASTIC FENCE-POST.

1,118,808.

Specification of Letters Patent.

Patented Nov. 24, 1914.

Application filed March 13, 1914. Serial No. 824,499.

To all whom it may concern:

Be it known that I, FLOYD A. RICE, a citizen of the United States, residing at Springfield, in the county of Clark, and State of Ohio, have invented new and useful Improvements in Plastic Fence-Posts, of which the following is a specification.

The present invention relates to plastic fence posts, and especially to fence wire 10 clamps which are associated with the posts in such a manner as to reinforce the same, but which may be readily forced into engagement with the wires to retain the same upon the post.

15 The invention further resides in the construction, combination and arrangement of parts set forth in the following specification and falling within the scope of the appended claim.

20 In the drawings: Figure 1 is a detail longitudinal sectional view illustrating a post provided with a modified form of clamp, Fig. 2 is a detail vertical sectional view of the same, Fig. 3 is a detail perspective view 25 of the clamp, Fig. 4 is a central longitudinal sectional view through the same, and Fig. 5 is a bottom plan view of the same.

Referring now to the drawings in detail, 1' designates a post which is constructed 30 from reinforced plastic material, and which may be formed of any desired size. Embedded within the post 1', when the same is being formed within a suitable mold, and arranged at desired spaced intervals are metallic clamps 2'. These clamps each comprise a body member 3' which has its sides or edges centrally incurved or of an arcuate formation, as clearly shown in the drawings, and one of the enlarged ends of 35 the body is preferably rounded to provide, what I will term, an eye 4', through the opening of which is passed a rod 5'. This rod may, if desired, extend the entire length of the post and is adapted to normally sustain 45 the clamps within the post. The other enlarged end of the clamp is centrally formed with a reduced oppositely curved finger 6', while the edges of the said end are formed with downwardly extending round- 50 ed fingers 7'. So it will be noted that the finger 6' is arranged intermediate of the fingers 7', and the clamp or plate 2' is embedded within the post to the juncture of the fingers 6' and 7'.

55 The oppositely rounded or angular tongues provide a substantially wedge-shaped mouth,

so that when a line wire is arranged therebetween the fingers will have a tendency to prevent the unslacking of the wire, and in fastening the wire to the fence, the finger 6' is bent downwardly over the wire and against the face of the post, while the fingers 7' are bent around the wire and upwardly and also into engagement with the said post. The fingers 6' and 7' of the clamp or plate 2' are, of course, formed of some malleable material so that the same is ductile under the blow of a hammer, but also the material from which the said fingers are formed will not angularly spread when bent over the wire 8', and by the peculiar arrangement of the fingers, as afore stated, the wedge-shaped mouth provided by the fingers permit of the fingers binding against the wire, and so an outward or a longitudinal movement of the wire is effectively prevented. The body of the clamp 2' is provided upon one of its faces with a longitudinally extending substantially V-shaped lug 9 which is arranged parallel with and between its central finger and its eye 4'. The opposite face of the body of the clamp, at the juncture of the finger 6' is inclined upwardly and rearwardly to provide a second lug 10, and the end of this lug is inclined downwardly, as at 85 11, and terminates only a short distance from the opening through which the rod passes. The sides of the lug 10 are beveled or inclined toward the end of the tie provided with the fingers, as indicated by the numerals 12, and the peculiar construction and arrangement of the lugs provides the body with additional sustaining elements so that the said clamp cannot move laterally, when 90 firmly embedded within the post, regardless 95 of the longitudinal pull upon the wire 8'.

From the above description, taken in connection with the accompanying drawings the simplicity of the device, as well as the advantages thereof will, it is thought, be 100 perfectly apparent to those skilled in the art to which such inventions appertain without further detailed description.

Having thus described the invention, what I claim is:

105 In combination with a plastic post, of a wire fence clamp having its body within the post, said clamp having one of its ends provided with an eye, a rod within the post passing through the eye, the body of the 110 clamp having its opposite faces provided with angularly arranged lugs, the end of

the clamp beyond the lugs being formed with a central finger and with side fingers, the central finger being disposed angularly in one direction, the side fingers being disposed angularly in an opposite direction to provide a flaring or wedge-shaped mouth between the upper and side fingers for the reception of a fence wire, the said fingers being formed of bendable material and adapt-

ed to be forced over the wire in opposite directions. 10

In testimony whereof I affix my signature in presence of two witnesses.

FLOYD A. RICE.

Witnesses:

ADAM FINK,
GUY O. CLARK.
